UNITED STATES PATENT OFFICE.

HENRY C. SEIPP, OF PITTSBURG, PENNSYLVANIA.

TIE OR HANGER FOR BUILDINGS.

No. 829,234.

Specification of Letters Patent.

Patented Aug. 21, 1906.

Application filed June 28, 1905. Serial No. 287,386.

To all whom it may concern:

Be it known that I, HENRY C. SEIPP, a resident of Pittsburg, in the county of Allegheny and State of Pennsylvania, have invented a new and useful Improvement in Ties or Hangers for Buildings, &c.; and I do hereby declare the following to be a full, clear, and exact description thereof.

My invention relates to a tie or hanger, and has special reference to such a tie or hanger which is adapted for use either in tying walls together or for hanging joists.

The object of my invention is to provide a simple and efficient tie or hanger which will not only do away with the forming of large tying walls in building stone for the end of the tie, but one which can be used in a single small circular hole and will form a stronger and cheaper form of tie than the ones most generally used.

A still further object of the invention is to provide such a hanger which will not only do away with the tedious, laborious, and expensive forming of the recesses in the beams of a building for the ends of the hanger, but will enable the same to be held within small bored holes in the beams for supporting the joists and will be cheaper and stronger than the ordinary hanger now in use.

To these ends my invention consists, generally stated, in the novel arrangement, construction, and combination of parts, as hereinafter more specifically set forth and described, and particularly pointed out in the claims.

To enable others skilled in the art to which my invention appertains to construct and use my improved tie or hanger, I will describe the same more fully, referring to the accompanying drawings, in which—

Figure 1 shows a vertical section of a building-wall with my improved tie or hanger applied thereto as a wall-tie. Fig. 2 is a plan view of a portion of a stone block, showing the end of the tie in position. Fig. 3 is a perspective view of the tie or hanger in this form. Fig. 4 is a plan view of another form of the tie or hanger applied to a beam and joist of a building and showing the same in use as a joist-hanger. Fig. 5 is a perspective view of the tie or hanger in this form. Fig. 6 is a vertical section on the line 6 6, Fig. 4.

Like symbols of reference herein indicate like parts in each of the figures of the drawings.

As illustrated in the drawings, 1 represents

a wall of a building, and when being constructed for the usual granite or stone building is generally made of the granite or stone front 2, formed of the blocks 3, and the rear brickwork 4 against the same. The front 2 and brickwork 4 are required to be tied together by the tie or hanger 5, and such tie consists of a flat piece of metal which is formed or bent to shape to provide the flat body portion 5', the right-angle flat portion 6 at one end of said body portion, and the semicircular or U-shaped gutter-supporting portion 7 at the opposite end of said body portion. This portion 7 is bent or formed at right angles to the flat portion 5' and has the open outer side 7'' and open ends 7''. In each of the blocks 3 of the outer or front walls 2 is a small circular hole 3', which is bored, drilled, or formed therein in any suitable manner, and as these blocks and rear brickwork 4 are built up in forming the wall 1, as shown in Fig. 1, the tie 5 connects each one of said blocks with said brickwork by fitting between each of said blocks and within said brickwork. This is accomplished by placing the grooved end portion 7 of the tie 5 within the hole 3' in each block 3 as it is placed in position on the wall 1 and allowing part of the flat body portion 5' of the tie to rest upon the block containing such hole and generally upon the mortar 2' placed thereon, while the other parts of said body portion and the angular portion 6 can rest upon the brickwork 4, which is built up to this point. The mortar 2' is then placed over such block 3 and body 5' of the tie 5 on said block, which will also fill up the hole 3' in said block and grooved seat 7' in the U-shaped anchoring end 7, and then another block is placed on said block and on said mortar, so that the tie is secured in the space 2' between these blocks and after which the brickwork 4 is built up around the body of said tie and angle portion 6 thereon and against the newly-placed block 3, which operation or process of forming the wall 1 is continued until said wall is completed.

When the tie or hanger 5 is to be used as a hanger for the joists of a building, it is formed with the U-shaped body portion 8, as shown in Figs. 3 and 4, having the flat bottom portion 8' and side portions 8'' extending up from the same, and a semicircular or gutter-supporting portion 7 extends out at right angles from each of the ends of said side portions, which is provided with the open outer

top 7" and open ends 7". In such a shape the hanger is applied to the beam or joist 9 by having two holes 10 within such beam or joist above the neutral axis thereof, and within 5 in said holes the two portions 7 on the hanger are placed, so that such a hanger is anchored or hung thereby from said beam or joist, and then the cross beam or joist 11 can be placed under the beam or joist 9 and within the 10 hanger, such beam or joist 11 resting on the bottom portion 8' of said hanger and being supported thereby. If desired, a bolt 12 can be placed within the grooved seat 7' in the 15 U-shaped ends 7 of the hanger, so that it can extend through the beam or joist 9 and be secured therein by means of a washer 12" and nut 12' at one end thereof.

It will be obvious that my improved tie or hanger may be used for a variety of purposes 20 other than those described and that various modifications and changes in the design and shape of the same may be resorted to without departing from the spirit of my invention or sacrificing any of its advantages. It will 25 thus be seen that my improved tie or hanger can be made by hand or machine and when in use will form a firm and substantial support for the wall or joist. It can be applied to its uses readily and easily and when used 30 as a wall-tie will allow the mortar to get into

the end and around the same in its anchoring-hole so as to have a greater tying and binding action than in the ordinary devices of this character, while it will also be seen that when it is used as a joist-hanger it will 35 not be liable to slip from or out of the joist or beam holding the same by reason of its anchoring ends fitting within and conforming to the supporting-holes for the same.

What I claim as my invention, and desire 40 to secure by Letters Patent, is—

1. As a new article of manufacture, a tie or hanger having a body portion, and an anchoring portion bent out at right angles from said body portion at one or both ends to form 45 a U-shaped gutter-supporting portion which is open at its side or top and ends.

2. A supporting device for walls, joists, &c., formed of a bent U-shaped body portion, and an anchoring portion bent out at 50 right angles from each end of said body portion to form a U-shaped gutter-supporting portion which is open at its side or top and ends.

In testimony whereof I, the said HENRY C. 55 SEIPP, have hereunto set my hand.

HENRY C. SEIPP.
